UNITED STATES PATENT OFFICE.

JOSEPH ANTOINE PAQUETTE, OF HULL, QUEBEC, CANADA.

CONTRACTIBLE SHAFT.

No. 872,538.

Specification of Letters Patent.

Patented Dec. 3, 1907.

Application filed March 30, 1907. Serial No. 365,586.

To all whom it may concern:

Be it known that I, JOSEPH ANTOINE PAQUETTE, of 64 Lake street, city of Hull, Province of Quebec, Canada, have invented certain new and useful Improvements in Contractible Shafts, of which the following is a specification.

My invention relates to improvements in contractible shafts, and the objects of my invention are to provide an exceedingly cheap and simple form of shaft particularly adaptable for winding paper rolls on and which releases after the roll has been wound thereon by reducing in diameter, and thus readily freed from the roll.

It constitutes essentially the shaft having a movable section, and means operable from the end of the shaft for freeing said movable section and allowing it to move inwardly, as hereinafter more fully set forth and described in the accompanying specification and drawings.

In drawings, Figure 1 shows a longitudinal sectional view through the shaft. Fig. 2 shows a top view of a portion of the same. Fig. 3 shows a transverse sectional view on the line 2—2 Fig. 1. Fig. 4 shows an enlarged perspective view on the lines 3—3 Fig. 1.

In drawings like figures of reference indicate corresponding parts in each figure.

Referring to the drawings, A is the shaft, which may be constructed of any desirable material and in any suitable shape. The shaft has at one side thereof a longitudinal recess *a* cut therein, within which a movable section B of the shaft is adapted to fit, the depth of the recess being greater than that of the section whereby the same may move inwardly, and a space may be provided for the means of operating the section.

The section is held from excessive outward movement by means of a plurality of pins *b* and *c*, which extend transversally thereof, and have their inner ends slotted at *d* to receive pins *f*, which extend transversally through the shaft, recesses *g* being provided into which the said pins extend.

The movable section is moved by means of a plurality of wedges *h*, which are secured to, or formed integral with a bar C, which ex-

tends longitudinally at the bottom of the recess *a*. This bar is secured at one end to a rod D, which extends through the end of the shaft and preferably is provided with a round end *i*, for convenience in operating. Slots *J* are provided in the rod B, through which the pins *b* and *c* extend, whereby the rod may be operated without disturbing the pins. The section B is provided on its under surface with a plurality of recesses K, having inclined faces *l*, adapted to co-act with the wedges *h* on the bar C, to cause the section B to move outwardly when operating rod D is pulled out from the shaft.

In operation the rod D is pulled to its outermost position causing section B to be moved outwardly, and the cross-section of the shaft is preferably such that in this position the periphery of the shaft will be exactly cylindrical. The paper or other material is then rolled on the shaft and when it is desirable to free the shaft, the rod D is pushed inwardly, permitting the section B to move inwardly, thus reducing the diameter of the shaft at one point and enabling the same to be readily pulled out. This shaft will be found of great use in paper mills, for when solid shafts are used to roll the paper on, they frequently bind and it becomes necessary to destroy the whole roll of paper in order to free the shaft. It is evident, however, that the application of the contractible shaft is not limited to paper rolls, but could be used wherever the function of a reducible diameter could be used to any advantage.

While I have, therefore, described the device in great particularity of detail, in the accompanying specification, yet it will be readily understood that in carrying out the invention, changes may be made within the scope of the appended claims, without departing from the spirit of the invention.

What I claim as my invention is:

In a contractible shaft, the combination with the shaft having a longitudinal slot therein, of a rod in the bottom thereof having apertures therethrough, means for actuating the rod from the end of the shaft, recesses in the bottom of the slot in the shaft below the apertures in the rod, outwardly movable sections located in the outer part of

the slot in the shaft, pins secured thereto, extending through the apertures in the rod, and into the recesses in the bottom of the shaft, and having slots in their extremities, 5 and pins extending transversely across the recesses in the shaft and through the slots in the said pins, as and for the purpose specified.

Signed at the city of Ottawa, in the Province of Ontario, this 16th day of March, 1907.

JOSEPH ANTOINE PAQUETTE,

Witnesses:

R. S. SMART,
WM. A. WYMAN.
